UNITED STATES PATENT OFFICE.

JOHN MAURICE POWELL, OF LOS GATOS, CALIFORNIA.

SPIKE-HOLDER.

1,009,568.

Specification of Letters Patent. Patented Nov. 21, 1911.

Application filed April 5, 1911. Serial No. 619,029.

To all whom it may concern:

Be it known that I, JOHN M. POWELL, a citizen of the United States, and a resident of Los Gatos, in the county of Santa Clara 5 and State of California, have invented a new and Improved Spike-Holder, of which the following is a full, clear, and exact description.

My invention relates generally to a device used in railroad construction and more particularly it involves an attachment adapted to be brought into engagement with the base plate of a rail and into contact with the head of a spike whereby the spike is held against displacement.

The object of my invention is to provide a spike holder, preferably made of a single piece of material, having parts thereon for engagement with a tie plate or rail chair 20 and another portion for engagement with the web of the rail, the said holder when in normal position being in contact with the head of a spike, whereby the spike is held against loosening and the danger of spreading rails is obviated.

A further object of my invention is to provide a simple and effective device of the type described which may be produced at a low cost of manufacture and by reason of 30 its construction will effectively hold the spikes in engagement with the ties whereby the danger of loose spikes is prevented.

Reference is to be had to the accompanying drawings forming a part of this specification in which like characters of reference denote corresponding parts in all the views, and in which—

Figure 1 is a plan view of a rail, together with the tie plate and spike, the spike holder being in normal position; Fig. 2 is a sectional view on the line 2—2 of Fig. 1; Fig. 3 is a similar sectional view but showing a form of holder especially adapted to engage the base of the rail, the tie plate 45 being omitted; Fig. 4 is a perspective of a form of holder shown in Figs. 1 and 2; Fig. 5 is a perspective view of the form shown in Fig. 3.

My holder is made preferably of integral 50 construction, as shown in Figs. 4 and 5, wherein the piece of metal 1 has its end portion 2 of channeled formation whereby the side portions 3 result which tend to stiffen the said portion, the opposite end of 55 the said material 4 being extended at an

angle to the portion 2 whereby a bearing surface is provided, the ends of the bearing surface being downwardly bent as at 5 and provided with lugs 6. The bearing surface 4, preferably at the base of the portion 2, is swaged as at 7 in order to provide a pocket 60 into which the head of the spike 8 may be securely engaged when the holder is in normal position, as shown in Figs. 2 and 3.

Referring particularly to Fig. 4, it will be noted that the bearing surface 4 is extended for a sufficient distance beyond the swaged portion 7 in order to permit the lugs 6 thereon to engage under the tie plate and against the tie 9, this tie plate being of 70 greater width than the base of the rail 10. In the form shown in Fig. 4 the bearing surface need not be extended beyond the swaged portion 7 any greater distance than enough to merely allow the head of the spike 8 to 75 be seated in the pocket 7.

In order to avoid excessive use of material as well as to make the lugs 6 independently resilient, the bent portion 5 is provided with a central recess 11, the depth of the recess 80 in each of the forms shown permitting the lugs 6 to engage irregularities in the surface of the tie 9, thereby making it unnecessary to have a plane surface on the said tie.

The normal position of my holder is 85 shown in Fig. 1 wherein the head of the spike 8 is securely positioned in the pocket formed by the swaged portion 7. The upper end of the portion 2 is securely engaged against the upper flange of the rail and the 90 lugs 6 are in engagement with the under side of the base of the rail or with the tie plate under the rail, this position being obtained by taking one of the holders and bringing the upper end portion thereof into engagement with the rail and driving the lugs 6 beneath the base thereof until the head of the spike 8 is securely seated in the swaged portion 7.

It is apparent that my spike holder will effectively hold the spike in position in the tie and that removal of the holder is difficult by reason of the fact that it is engaged at its end portions and being made preferably of steel it possesses strength and rigidity. By securely holding the spike in position in the tie, the danger of spreading rails is avoided and the possibility of train wrecking minimized. The holder has a further function in that it will tend to hold the

rails in line should they become broken, whereby an added element of safety is obtained.

While I have shown my spike holder of a preferred form, together with a slight modification thereof, it is obvious that changes in the form, shape, and size of the holder may be varied at will to meet different conditions without departing from the spirit 5 and scope of the invention as set forth in the following claim.

Having thus described my invention, I claim as new, and desire to secure by Letters Patent:—

15 A spike holder made up of a single piece of metal having one end portion thereof of channeled formation, the outer end of which is in engagement with the flange of a rail, the said channeled portion extending angularly therefrom, a plane bearing surface adjacent the said channeled end portion, the

other end of the said holder being provided with over-turned lugs integral therewith, the said plane bearing portion being provided with a pocket on the under side thereof and closely adjacent the said lugs, whereby when the outer end of the said channeled end portion is placed against the web of a rail, the said lugs may be driven under the flange of the said rail with the head of the spike in engagement with the said flange positioned within the pocket in the said plane bearing surface whereby the said spike will be held against removal. 25 30

In testimony whereof I have signed my name to this specification in the presence of two subscribing witnesses.

JOHN MAURICE POWELL.
